UNITED STATES PATENT OFFICE.

A. P. LIGHTHILL, OF BOSTON, MASSACHUSETTS.

IMPROVEMENT IN CATARRHAL SYRINGES.

Specification forming part of Letters Patent No. 50,722, dated October 31, 1865.

To all whom it may concern:

Be it known that I, AUGUSTUS PONHAM LIGHTHILL, of Boston, in the county of Suffolk and State of Massachusetts, have invented a new and useful Improvement in Catarrhal Syringes; and I do hereby declare the same to be fully described in the following specification and represented in the accompanying drawings, of which—

Figure 1 denotes a side view, Fig. 2 a front elevation, Fig. 3 a top view, and Fig. 4 a longitudinal section, of the jet-tube and the foraminous nose or bulb of a catarrhal syringe, my invention having special reference to such parts only. Fig. 5 is a horizontal section of the bulb.

Prior to my invention it has been common to construct of a spherical form the spray-bulb of a catarrhal syringe. Instead of so constructing it, I make it elliptical, or thereabout, in its longitudinal as well as in its transverse section, the same being as shown in the drawings, in which—

a denotes the bulb, and *b* the stem or jet-tube, on whose extremity the said bulb is fixed. The bulb is hollow or chambered and foraminous, and opens into the bore of the jet-tube.

Instead of curving the jet-tube in the ordinary way, I give to it a sudden bend, *c*, close to its junction with the bulb, and so that the axis of the bulb may stand at very nearly a right angle to that of the straight part of the tube, the same being as shown in the drawings.

By reason of the peculiar shape of the flat bulb, which may be said to be formed of two concavo-convex elliptical disks connected together at their edges, and being arranged with respect to the tube as shown in the drawings. Such bulb will enter the passage leading from the throat to the nose of the patient to much better advantage than will a spherical bulb, and, besides, by my arrangement of the bulb

or formation of the stem with a sudden bend, *c*, so as to bring the bulb close to the straight part of the stem, the bulb can be easily inserted in the mouth of the passage without contact of the stem with the back part of the tongue of the patient.

The great difficulty experienced in the use of the common syringe, whose stem has a long curve or bend between its straight part and the bulb, is the almost unavoidable contact of this bend with the back of the tongue of the patient while the operator is in the act of introducing the bulb to the nasal passage for the purpose of injecting a fluid therein. As most persons are very sensitive to any such touching of the back part of the tongue, it being productive of more or less instantaneous muscular action of the throat and stomach—an action which is often a serious impediment to the operator—the advantage of my improved form of bulb and the jet-tube will be apparent.

The difference between my improved bulb and stem and those heretofore in common use for catarrhal syringes will be seen by comparing it with Fig. 6, which is an illustration of the common bulb and stem.

What, therefore, I claim as my invention is—

1. The construction of the bulb *a*, elliptical or oval in its longitudinal and transverse sections.
2. The improved arrangement of the bulb and its stem, or the construction of the latter with the sudden bend at its junction with the bulb, whereby the axes of the bulb and stem are caused to be at or nearly a right angle to each other, as represented.

A. P. LIGHTHILL.
